FIG. 3

UNITED STATES PATENT OFFICE

2,589,191

GROOVE DRESSING TOOL

Charles A. Laase, Genoa, Ohio, assignor to The Timken Roller Bearing Company, Canton, Ohio, a corporation of Ohio

Application November 10, 1947, Serial No. 784,970

7 Claims. (Cl. 51—254)

1

This invention relates to tools for dressing or grinding the walls of grooves, more particularly tools for dressing or grinding the bottom of the helical groove of a feed wheel or cylinder such as the feed wheel of a centerless grinding machine. The invention has for its principal objects means for easily and more accurately dressing or grinding the bottoms of such helical grooves and for easily accommodating the nice adjustments required in such a device.

Another object of this invention is to provide an improved wheel dressing and grinding wheel driving means and grinder guiding means that will enable the cutter or grinder to operate at a higher and constant speed and to dress the helical groove of the wheel in a more accurate manner so that the resulting work piece and guide wheel will operate at a very high degree of accuracy.

The invention consists principally in a grinding wheel adapted to be set to conform to the lead of a helical groove and mounted on a slideable hanger that is provided with means engaging a side wall of a groove, whereby the grinding wheel may be fed along the groove by rotating the feed wheel or other member whose groove is being dressed. The invention further consists in the groove dressing tool and in the parts and combinations and arrangements of parts hereinafter described and claimed.

In the drawings:

Fig. 1 is an elevational view of the device incorporating the invention,

Fig. 2 is a plan view of the device looking in the direction of the line 2—2 of Fig. 1,

Fig. 3 is a sectional view taken along the line 3—3 of Fig. 2,

Fig. 4 is a sectional view taken along the line 4—4 of Fig. 2; and

Fig. 5 shows an elevational view of a portion of a guide wheel.

The present guide or control wheel is of the same general type as that illustrated in United States Patent No. 1,722,023 which shows the guide wheel having a helical groove in which the work supporting surface of the groove must be dressed or ground from time to time. In this patent the groove grinder guiding is done by the side walls of the groove or channel which become worn in use and regrounding, thereby reducing the accuracy of the machine. The specific guide wheel 1 comprising the present invention is shown in Fig. 5 on which spaced collars are formed, on one side of which is a guide channel 1a adjacent which surface 1b is formed which is the surface to be operated upon and adjacent which the other collar is located. A tapered roller B engages the surface 1b and the roller is centerless ground by wheel A in the customary manner.

2

Roller B is supported against one of the guide wheel collars in addition to engaging surface 1b. This structural organization results in a more accurately machined surface on the roller B because the guide channel is distinct from the roller supporting portion of the guide wheel so that subsequent regrindings of the surface 1b do not disturb the spacing between the said collar and surface 1b.

10 The guide wheel 1, which is the object worked upon for the grinder to be described, is rotatably supported on a spindle 2 suitably rotatably mounted in a base 3 of a grinder on which it is customarily supported. Removably secured to the upper part of the base 3 is a fixture 4 provided with a double way guide 5 on which a slide 6 is slidably mounted. Adjustably supported on the slide 6 is a prime mover 7 preferably in the form of an electric motor operated by an electric current having a frequency in the neighborhood of 180 cycles and which is belt-connected to a spindle 8 rotatably mounted in a quill 9 that is slidably received in a clamping sleeve 10. A grinding wheel 11 is secured to the spindle 8 adjacent the opposite end of the quill from the belt drive and is intended to engage the surface 1b of the work piece.

The sleeve 10 is supported on a slide 12 that is supported on a dovetailed column 13. Slide 14 is supported on column 13 opposite slide 12 and is attached to slide 12 through member 14'. Slides 12 and 14 are adjusted vertically as a unit by means of screw 15 and crank 16 with respect to slide 6. This vertical adjustment is necessary to apply or withdraw the grinding wheel 11 to or from the guide wheel 1 as required. The motor, grinder and belt are supported on the member 14 by suitable supports and move as a unit with respect to slide 6. The slides 12 and 14 are moved as a unit by screw 15 threaded into slide 13. The screw is rotatably received in a suitably shaped formation in member 14' and is rotated by crank 16.

45 The carrier 17 for the grinding wheel dressing tool 18 is also carried by slide 12. The tool 18 is secured by screw 19 into member 20 that is slidably received in carrier 17. The lead screw 22 is threaded into the nut 23 so that when screw 22 is rotated, the member 20 will be moved parallel to the longitudinal axis of the spindle 8, thereby moving tool 18 across the surface of the grinding wheel 11.

50 The carrier 17 is pivotally supported on the slide 12 by means of a pin 25 secured in slide 32 on which slide 26 is supported. The carrier 17 and member 20 are supported on the slide 26. Pivotal adjustment is made by means of two screws 27 and 28 rotatably supported in ears secured to the slide 32. The screws contact an

extension 29 of slide 26 and by means of pointer 30 secured thereto and indicia 31, the degree of tilt to slide 26 is determined, which determines the angle the cutting surface of grinder 11 makes with the horizontal to thereby properly grind surface 1b in the guide wheel 1. Vertical adjustment of slide 32 relative to slide 12 to feed tool 18 toward the grinder 11 is made by screw 33 threaded into the slide 32 and rotatably received in a bracket 35 secured to slide 12. Slide 26 may be locked in any angularly adjusted position by member 26' which has a locking screw therein that is threaded into the slide 32 so as to clamp the two slides together. A graduated operating member 34 makes possible a very fine adjustment of the tool 18 toward and away from the grinding wheel 11.

Supported on the slide 12 is another slide 36 on whose lower end a follower 37 is mounted which is adapted to engage channel 1a in the guide wheel 1. This slide is vertically adjustable by means of a screw 38 and lock nut 39 threaded into a bracket integrally associated with the slide. The screw 38 engages an abutment on slide 6. The slide is locked in adjusted position by clamp members 40, each of which is provided with screws that engage the slide 36.

From the foregoing it is evident that a device has been provided that makes possible the grinding of any desired angle to surface 1b that will provide for a constant dressing of the wheel to said angle and that will drive the grinding wheel at a high and substantially constant speed.

What I claim is:

1. A grinding machine comprising a guide wheel having a helical work piece engaging surface and provided with a complementary guide channel adjacent the work piece engaging surface; a grinder to dress said work piece engaging surface; a follower operable in the guide channel; and means connecting the follower and grinder so that the path of movement of the grinder will be that imposed thereon by said follower as it is moved through said channel.

2. A grinding machine comprising a guide wheel having a helical work piece engaging surface and provided with a complementary guide channel adjacent the work piece engaging surface; a grinder to operate on said surface; a high frequency motor to operate said means at a high and constant speed; a follower to guide the movement of said means and operable in said channel; a dressing tool for said grinder; means to adjust said dressing tool relative to said grinder; and means to move said grinder and said follower toward and away from the guide wheel.

3. A grinding machine comprising a guide wheel having a helical work piece engaging surface and provided with a complementary guide channel adjacent the work piece engaging surface; a grinder for said surface; a high frequency motor to operate said grinder at a high and constant speed; means to support said grinder and motor; a follower mechanism engageable in the channel to guide the motion of said grinder; means to adjust said follower toward and away from the guide wheel; a tool to dress said grinder; means to adjust said tool relative to said grinder; and means to move said grinder, said dressing tool and said follower toward and away from the guide wheel.

4. A grinding machine comprising a guide wheel having a helical work piece engaging sur-

face and provided with a complementary guide channel adjacent the work piece engaging surface; a support for the guide wheel to enable it to rotate on its longitudinal axis; a slide movable relative to said support parallel to the longitudinal axis; means to support a grinding wheel adjacent said surface and mounted on said slide; a high frequency motor to operate said grinder at a high and constant speed and mounted on said slide; a follower adjustably mounted on said slide and engageable with said channel, said follower guiding the movement of said grinder; a dressing tool for said grinder adjustably supported on said slide; and means to move said slide toward and away from the rotatable support.

5. In a centerless grinder; means to feed work pieces to said grinder which includes a rotatable guide wheel provided with a helical work supporting surface and a complementary helical follower channel; a grinder to operate on said surface; a high frequency motor to operate said grinder; means engageable in said channel to guide the movement of the grinder as it traverses the rotatable guide; adjustably mounted means to dress said grinder; and a slide means to support said motor, said grinder and said follower for movement relative to said guide wheel.

6. A grinding machine comprising a guide wheel having a helical work piece engaging surface and provided with a complementary guide channel adjacent the work piece engaging surface; a support for the guide wheel to enable it to rotate on its longitudinal axis; a slide movable relative to said support parallel to the longitudinal axis; means to support a grinding wheel adjacent said surface and mounted on said slide; a high frequency motor to operate said grinder at a high and constant speed and mounted on said slide; a follower adjustably mounted on said slide and engageable with said channel, said follower guiding the movement of said grinder; a dressing tool for said grinder adjustably supported on said slide; and means to move said slide toward and away from the rotatable support.

7. A grinding machine comprising a guide wheel having a helical work piece engaging surface and provided with a complementary guide channel adjacent the work piece engaging surface; a grinder to operate on said surface; a high frequency motor to operate said means at a high and constant speed; a follower to guide the movement of said means and operable in said channel; a dressing tool for said grinder; means to adjust said dressing tool relative to said grinder; and means to move said grinder and said follower toward and away from the guide wheel.
